UNITED STATES PATENT OFFICE

CLARENCE W. UTZMAN, OF CHICAGO, ILLINOIS, ASSIGNOR, BY MESNE ASSIGNMENTS, TO
UNITED STATES GYPSUM COMPANY

PLASTER BOARD

Application filed August 12, 1922. Serial No. 581,361.

This invention relates to plaster board or the like, and to the method of making it. Plaster board is usually employed as a wall covering in substitution for lath and plaster.

Among other objects, the invention is intended to supply a protected edge for plaster-board which shall be of neat appearance, secure and durable.

The invention resides in the novel constructions, combinations and methods, hereinafter described or claimed, for carrying out the above stated object and such other objects as will hereinafter appear.

In the drawings:

Fig. 1 is a fragmentary perspective showing an end of the plaster board and a protected edge thereof embodying this invention.

Fig. 2 is a cross section through the protected edge on the line 2—2 of Fig. 1, and

Figs. 3 and 4 respectively, are sections similar to Fig. 2 but showing modifications of the form shown in Fig. 2.

Referring to the drawings, the body 5 of the plaster board is of plaster or the like, with or without admixture of other ingredients. The body 5 has a top cover sheet 6 and a bottom cover sheet 7, preferably of heavy paper or the like adhered to the faces 20 of the body. One of the covering sheets, the sheet 7 in the illustrative instance, is folded at its margin 8 so as substantially to cover the edge of the plaster body 5. To facilitate the folding of the margin 8, the sheet 7 is preferably scored at 9 along the line upon which the margin is to be folded.

The extreme edge of the margin 8 may be located in any desired relation to the edge of the top sheet 6. For instance it is not indispensable that the edge of the margin 8 contact with the top sheet 6, or that the margin 8 extend entirely across the edge of the body 5.

While the inner face of the margin 8 may adhere with a certain degree of security to the edge of the plaster body 5, that adhesion is not wholly dependable under all circumstances, and it is one of the objects of this invention to provide an efficient mechanical bond between the margin 8 or its equivalent

and the plaster body to hold the margin 8 in its proper protective relation to the edge of the body, or else to supplement the adhesion to the same end.

For illustration, Figs. 1 and 2 show a perforation 10 of the margin 8, performed by striking out a portion of the material at the margin, so as to leave an aperture in the material of the margin to be engaged by the plaster or similar body material, some of which may project into the aperture and extend through it and to the outer surface of the margin 8 surrounding the aperture. Thus an integral part 11 of the body material may be made to engage the outer face of the margin 8 to hold it securely to the body.

To enhance and facilitate the result just described, the outer surface of the margin 8 may be concaved into a cup-like form substantially concentric with the aperture, so that the plaster body material may project through the aperture and extend into the cup-like concavity, while not projecting materially beyond the normal plane of the outer face of the margin 8. This effect is illustrated in perspective in Fig. 1.

Fig. 3 illustrates a slightly different form for producing the same general result, the margin 8 being shown as penetrated to form a more or less ragged aperture 12 therein having burrs 13, so to speak, engaging with the plaster of the body material. Here again some of the material of the body makes an anchorage against outwardly disposed parts of the margin 8.

In Fig. 4 the aperture 14 is formed so as to leave a substantial tongue 15 to be engaged by the plaster body material, part of which may also anchor against the outwardly disposed shoulder 16 of the tongue.

It will be observed that the various exemplary deformations of the margin 8 provide efficient anchoring means located at intervals lengthwise the margin and occurring as frequently as may be deemed necessary to hold or assist in holding the margin in proper place. While the margin 8 is deformed at intervals for the purposes described, the margin between the deformations may remain intact and smooth to cover and protect the

- edge of the board on that area over which the margin extends. Of course the details of construction described may be variously modified.
5. In the process of making the plaster board, the body material in a suitable plastic state may be spread to a uniform thickness or layer on the bottom covering sheet 7, the margin 8 of which may be folded upon and in adhering contact with the edge of the plastic layer; and the top covering sheet 6 may then be applied; both sheets adhering to the plastic body material substantially throughout the width of the board being manufactured. The aforesaid deformations in the margin 8 may, if desired, be preliminarily formed, in which event said deformations may be caused to embed in or interengage with the plastic body material by effecting a slight spreading of the material when the margin is folded against the edge thereof; or the said deformations may be made in the margin 8 after the margin is folded upon the edge of the body material and while the latter is still in plastic state, so as to allow the plastic material to spread through the apertures of the margin and engage against the outwardly disposed shoulders thereof, to provide secure anchorages when the plastic material becomes set. The process may be conveniently carried out by continuously passing upper and lower covering sheets and an intervening layer of plastic body material between suitable spreading rolls and lateral devices for turning up the margins of the lower sheet and pressing them against the edges of the plastic material, and deforming the margins to secure anchorages in the plastic material as aforesaid.
- 40 Having described my invention, I claim:
1. A plaster board comprising, in combination, a body of plaster or the like; covering material on the face of said body; and a folded cover sheet margin on an edge of said body and anchored thereto by portions of the body material protruding through apertured portions of the margin.
  2. A plaster board comprising a body of plaster interposed between sheets of fibrous material, one of said sheets having a perforated marginal portion folded over upon an edge of said body.
  3. A plaster board comprising a body of plaster interposed between sheets of fibrous material, one of said sheets having a marginal portion folded over upon an edge of said body and terminating short of the full width of said edge, said marginal portion having a plurality of perforations extending longitudinally thereof.
  4. A plaster board comprising a plaster body interposed between covering sheets of fibrous material, one of said sheets having a perforated marginal portion adapted to be folded over the edge surface of said body,

along a line substantially coincident with the perforations.

5. A plaster board comprising in combination a body of plaster or the like; normally imperforate fibrous cover material covering the opposite faces of said body and adhering thereto; and a margin of said cover material folded over an edge of the body and being rendered perforate by a series of openings, therein into which the material of the body extends, thereby providing anchorages with the plaster body, said margin being constructed and arranged to expose a substantial area of the plaster body at the edge of the board.

In testimony whereof, I have signed my name to this specification.

CLARENCE W. UTZMAN.
